CLAIM

The ornamental design for a display screen or portion thereof with icon, as shown and described.

DESCRIPTION

FIG. 1 is a front view of a display screen or portion thereof with icon, showing our new design in a first embodiment; and,

FIG. 2 is a front view of a display screen or portion thereof with icon, showing our new design in a second embodiment. The outermost perimeter, illustrated by a pair of dashed broken lines, represents a display screen or portion thereof and forms no part of the claimed design. The remaining dashed broken lines, illustrating portions of the icon, form no part of the claimed design.

1 Claim, 2 Drawing Sheets
